UNITED STATES PATENT OFFICE.

FREDERICK H. KNAPP, OF WESTMINSTER, MARYLAND, ASSIGNOR TO FRED H. KNAPP COMPANY, OF WESTMINSTER, MARYLAND, A CORPORATION OF MARYLAND.

CAN-LABELING MACHINE.

1,108,188.

Specification of Letters Patent. Patented Aug. 25, 1914.

Application filed April 2, 1912. Serial No. 688,058.

To all whom it may concern:

Be it known that I, FREDERICK H. KNAPP, a citizen of the United States, residing at Westminster, in the county of Carroll and State of Maryland, have invented certain new and useful Improvements in Can-Labeling Machines, of which the following is a specification, reference being had therein to the accompanying drawing.

10 This invention relates to labeling machines of the character designed to apply and affix labels to cans, cartons and the like. In the labeling machine art, it is customary to first affix one end of the label to the can or other article to be labeled, and to then impart rotary movement to the can whereby the label is wrapped about the can, and whereby the opposite or lap end of label, which has previously been supplied with a 20 coating of paste, will be affixed. Many constructions have been devised for applying paste to the lap end of the label, most of which have proven deficient and impractical to a large extent in use, for many reasons, among which may be mentioned the fact that the end of the label has not been thoroughly or evenly pasted, a large amount of paste has been wasted, and in those machines in which the pasting member normally rests, on the topmost of a supply of labels, the other labels become damp or moist, thus causing them to wrinkle or buckle and thereby damaging the same.

It is the main object of the present invention to overcome the above and other defects in prior machines, and to generally improve upon the lap end pasting mechanism in machines of this character, and to this end the invention includes novel and efficient pasting mechanism comprising a paste carrying member, intermittent in operation both in engaging the labels to paste the same and in presenting a new pasted surface or area to successive labels, all of which operations are automatic and governed and controlled by a can in its movement in a suitable runway.

While the machine is more especially designed for labeling cans, and while this term is used for convenience in the description and claims as the article to be labeled, this term is to be construed as a general one, and includes various types of cartons and packages, since it is obvious that the ma-

chine is susceptible of various uses and 55 adaptations.

In more particular detail, the invention includes an endless paste carrier supported from a paste receptacle beyond the end of the label receptacle, the operative end of the 60 endless carrier normally occupying a position above the supply of labels and spaced vertically therefrom and adapted to be intermittently moved so as to contact with the uppermost label and move the same from 65 the pile of labels by mechanism engaged by a passing can and also adapted to be intermittently moved lengthwise by a mechanism engaged by the passing can, so as to present a new pasted area to successive cans. 70

The invention also embraces a novel construction of endless paste carrier and associated feed therefor, thereby effectively overcoming the usual stretching and twisting of the belt in operation and insuring a 75 uniform feed from side to side of the belt.

Further, the invention includes novel supporting means for the paste receptacle and associated lap end pasting mechanism carried thereby permitting of quick and accurate adjustment and assembly and detachability of the parts, and regulating to a nicety, the extent of the coating of paste to the lap end of the label.

In practice it has been found that the supply of labels when in position on the support or label receptacle will usually sag, thereby presenting a substantially curved surface in outline, and it has therefore been found difficult to thoroughly and evenly coat the lap 90 end of the label from side to side, and to overcome these difficulties it is contemplated by the inventor to provide a novel supporting member for the operative part of the paste carrying member which engages the 95 label, whereby the paste carrying member assumes a position more accurately conforming to the usual curved outline of the supply of labels.

Other and further improvements in the 100 construction and novel details in the construction and arrangement of parts will be more particularly referred to in the description, to follow, which for a comprehensive understanding of the invention should be 105 considered in connection with the accompanying drawings forming a part hereof and wherein is disclosed for the purpose of illus-

tration convenient and satisfactory embodiments thereof.

In the drawings: Figure 1 is a side elevation of the machine, certain parts being shown in section, Fig. 2 is a side elevation (enlarged) of the lap end pasting mechanism, Fig. 3 is a top plan view of the same, Fig. 4 is a longitudinal section of the same, Fig. 5 is a section on substantially the line 5-5 of Fig. 3 looking in the direction of the arrows, and, Fig. 6 is a front elevation (enlarged) of the lap end paste receptacle and associated mechanism, parts being shown in section. Fig. 7 is a side elevation 15 of a modified and preferred form of trip mechanism for moving the paste applying member lengthwise, Fig. 8 is a top plan view of the same, and, Fig. 9 is an end elevation of the paste pot showing an adjustable bracket which constitutes a stop for limiting the vertical movement of the paste applying member, the said stop being adapted to be used in connection with a modified form of apparatus illustrated in the two 25 preceding views.

With more particular reference to the drawings wherein like reference numerals refer to corresponding parts throughout the several views, 1 designates diagrammatically, the framework of the machine. Suitably supported on the frame adjacent the forward end thereof is a paste receptacle 2 having therein a paste applying roll 3 adapted to be driven by any suitable means 30 and so positioned in the receptacle that the periphery extends above the top thereof and in the path of a passing can so as to place upon the periphery of the can a daub of paste. It is obvious that any of the 35 proved pick up pasting appliances may be used, as also means for moving the cans along the runway, such means as disclosed in the drawings being shown merely for the purpose of illustration and not constituting any part of the present invention. 40

The can runway is indicated by the numeral 4, and the means for feeding the cans longitudinally of the machine takes the form of an endless belt 5, cut away in the 45 drawings, and driven in any suitable manner.

6 is a label receptacle adapted to support a supply of labels which latter may be automatically fed upwardly in the receptacle as 50 by the usual spring pressed follower not shown. The forward upper end of the label receptacle is cut away, as at 7, thereby exposing the forward end of the label in order that the same may be contacted by the pasted portion of the can and picked up by the can in the rotary movement of the latter. The labels assume an inclined position in the receptacle, and suitably supported adjacent the top of the receptacle and toward the 55 rear thereof is a curling bar 8 of any de-

sired construction and operating in the usual manner to curl the label whereby it more readily conforms to the periphery of the can and is wound thereabout in the movement of the latter. The rear end of the label receptacle is cut away, at 9, whereby to expose the rear or lap ends of the labels in order that the same may be supplied with a coating of paste previous to being withdrawn from the receptacle by the moving 60 can.

The pasting mechanism for the lap end of the labels which constitutes the foremost feature of the present invention will now be described. The paste receptacle proper 10, 65 may be of any approved outline, the same being supported in a manner to be herein-after referred to, and adapted to receive a rotatable paste pick up roll 11, the periphery of the roll projecting above the upper end of the receptacle and extending substantially from side to side thereof. The paste receptacle is adapted to be positioned to the rear of the label receptacle and the roll 11 moves upon an axis extending transversely of the 70 machine, the shaft 11^a of the roll extending without the side of the receptacle and adapted to be driven in any suitable manner. The shaft 11^a is supported in the receptacle and prevented from endwise movement as 75 by collars 11^b and 11^c arranged to the outside of the receptacle and held as by bolts in any desired manner. The roll 11 is suitably keyed to the shaft 11^a whereby upon removing the collar 11^b the shaft may be 80 removed from the opposite side of the receptacle and the roller 11 taken out of the top of the receptacle and cleansed as desired. Upon one end of the shaft 11^a and to the outside of the receptacle is suitably 85 mounted a gear wheel 12, adapted to mesh with a pinion 13 supported at one end on a suitable shaft 14 supported in upwardly projecting ears or bracket members 15 at the sides of the receptacle. This shaft 14 supports a suitable roller 16 keyed thereto, 90 whereby upon removing the securing collar 17, the shaft may be removed from the roller and from the receptacle. 95

A swinging support conveniently U-shaped in outline is supported upon the shaft 14 and preferably comprises oppositely disposed arms 17' having a collar 17^a at one end, one of which is adapted to loosely fit over the shaft 14 between the bracket 15 and a suitable collar 15^a on the pinion 13, and the collar of the other arm being adapted to loosely fit over the opposite end of the shaft 14 between the bracket 15 and securing collar 17. Adjacent the free end of the arms 17' are apertured blocks 18 adapted to receive the arms 19 of a substantially U-shaped support 20. The U-shaped support is adapted for longitudinal adjustment relative to the arms 17' and is secured in adjusted position, 100 105 110 115 120 125 130

as by bolts 21. At opposite ends of the roller 16, toothed wheels 22 are provided, the same being adapted to be engaged by suitable chains 22* secured to opposite sides of an endless paste carrying belt 24, the said belt being adapted to engage over the roller 16 at one end and over the connecting arm of the U-shaped member 20 at an opposite end, movement being imparted to the belt by the 10 toothed wheels 22 of the roller 16, engaging the chains, as stated.

Projecting downwardly from the opposite arms 17 are suitable spring members 25 secured to the arms in any desired manner, 15 and resting at their lower ends on the upper edge of the receptacle 10. When the label receptacle is in position the forward end of the endless paste carrying member 24 projects over the upper surface of the labels at 20 the rear end thereof, and the function of the spring members 25 is to normally space said forward end of the endless carrier out of contact with the stack of labels. This feature constitutes an important element in the 25 improved construction, since as is customary, should the endless paste carrier remain in contact with the stack of labels, not only the uppermost label will absorb the paste, but the moisture will leak through to the 30 under labels and thereby cause the latter to become injured, as by wrinkling.

It is contemplated to intermittently and positively move the operative or forward end of the endless paste belt toward and 35 away from the supply of labels through its carrying frame, while maintaining the belt in its normal stretched or taut condition, as distinguished from flexing the belt so as to contact the same with the labels. In the upward movement of the carrying frame, the uppermost label, the lap end of which having received a coating of paste from the endless carrier, will stick to the carrier and be raised out of contact with the stack of labels 40 45 thereby providing against the supply of labels being effected by the moisture of the paste on the topmost label. Novel means is provided for so moving the carrier frame of the paste member, and while one of said 50 means may be employed, the best results are accomplished by two, one to each side of the machine to engage each side of the carrying frame and adapted to act simultaneously. Since the means at either side of the runway 55 are substantially duplicates, a description of one will suffice for the other.

26 is an elongated arm loosely supported upon a pivotal bearing 27, which latter is threaded to the side of the label receptacle 6. 60 Threaded to the outer end of the bearing 27 is an adjusting nut 28, while sleeved upon the bearing intermediate the arm 27 and nut 28 is a spiral spring 29 connected at one end to the arm or a part carried thereby and at 65 its opposite end to the nut 28. Secured to

the arm is an elongated, preferably flat plate 30 of a width to overlie the runway 4 and when moved to lowered position to lie flat upon the said runway and offer substantially no obstruction thereabove. The spring 70 29 is adapted to normally hold the plate 30 in an upper inclined position, whereby it may be engaged by a passing can and lowered into the said position flat against the runway. The tension of the spring 29 may 75 be regulated as desired, through the medium of the adjusting nut 28. Depending from the lower surface of the plate 30 to the outside of the runway, is a leaf spring 31, secured at one end as by bolts 32 to said plate 80 and having a curved opposite end adapted in the lowering movement of the arm 26 with the plate 30 to yieldably engage a contact plate 33 on the upper surface of the U-shaped arm 20 and secured to the block 85 18. As the spring arms 31 engage the said plates 33, there being one to each side of the runway and for each arm 31, the endless paste carrying member is lowered into yieldable engagement with the lap end of the 90 label and remains in lowered position only so long as the can is in engagement with the plate 30. Just as soon as the arm 26 and plate 30 are released by the can moving from engagement therewith, the said springs 31 95 will be automatically raised by the springs 29 so as to be in position to be engaged by a succeeding can. At the same time the spring 25 will raise the operative end of the endless paste carrier upward and with it the lap 100 end of the uppermost label which sticks thereto thereby being spaced from the supply of labels, the upward movement of the endless paste belt carrying frame being limited as by a bracket arm or arms 34 projecting upwardly from the paste receptacle 10 and adapted to overlie the side arms of the support for said paste carrier.

The U-shaped arm 20 which constitutes the support for the operative end of the endless carrier may be adjusted whereby to adapt itself to the carrier and take up any play therein, and a convenient formation for the forward end of the member 20 is a curve, as illustrated more particularly and somewhat exaggerated, in Fig. 6. This particular construction of support for the carrier is of especial advantage since it allows the endless paste carrier to conform when in operative position to the general outline of the labels, it being noted in this respect that the supply of labels, in practice, usually sags. While various forms of constructions may be provided for so contacting the operative end of the paste carrying member with the labels 115 from side to side of the latter, and while various modifications are within the spirit of the invention, the form of construction illustrated has been found very satisfactory in 120 practice. 125 130

When the endless paste carrier member is in position on the receptacle 10, it will be observed that the lower portion thereof engages over the roller 11 whereby to receive a coating of paste from the said roller 11, which latter is operated preferably intermittently, by the mechanism about to be described. Means may be employed to scrape the paste from the roller 11 and to thereby regulate the quantity of paste taken up by the same, the said means preferably including a scraper member 35 secured to the forward end of the receptacle 10 and having side flanges 35^a to engage over the sides of the roll and carrying an elongated member 36 laterally adjustable, as by a screw and slot connection 37, the said member 36 being adapted to engage the paste on the body of the roll 11, and this engagement may be regulated by fastening the screws and adjusting the member 36, to thereby regulate the quantity of paste taken up by the roll.

The means for intermittently actuating the endless belt or paste carrying member is preferably controlled by the movement of the can along the runway and is preferably made up as follows. Secured to the gear wheel 12, in any desired manner, is a suitable ratchet wheel 38, and loosely sleeved upon the shaft 11^a for rocking movement is a sleeve 39 at the lower end of a rocking arm 40 offset at its upper end, as at 41, and having a transversely extending plate 42 secured to the upper end of said offset portion 41. The plate 42 is substantially flat and is adapted in the rocking movement of the arm 40 to occupy a position when lowered flat against the runway 4, and offering substantially no obstruction above the latter whereby the can may readily ride over the plate. The arm 40 is preferably held in an elevated position whereby to position the plate 42 at an incline above the runway as by a spring arm 43, preferably constructed as shown, the same being secured at one end to a suitable boss 44 projected from the sleeve 39, and loosely sliding in a slotted support 45 secured to one wall of the receptacle 10. The slot of the member 45 is a terminal one whereby in the removal of the parts the spring 43 may readily be disengaged by a movement lengthwise of the support 45. Suitably pivoted to the arm 40, adjacent the offset upper end 41 thereof, is a dog of any desired construction 46, preferably spring held and adapted at its free end to engage the periphery of the ratchet wheel 38. The operation of this feature of the construction is obvious. As a can moves along the runway, being fed by the belts 5, the same contacts with the plate 42, thereby lowering the plate into contact with the runway and in the lowering movement swings the rocking arm rearwardly, which because of the engagement of the dog 46 with one of the ratchet

teeth of the wheel 38, will move the latter preferably one tooth, though this may be adjusted or regulated as desired. It will thus be seen that an intermittent movement to the belt is given each time a can passes over the plate 42, and should the machine not be in use the paste carrying member will remain stationary.

A suitable hand wheel 46^a may be provided upon the end of the shaft 11^a whereby to impart a preliminary and continuous movement to the endless paste carrier at the beginning of the operation of the machine in order to apply a coating of paste to the belt.

The depth of the coating of paste to the lap end of the label may be regulated by the adjustment of the label receptacle on its support, and with this and other objects in view the receptacle 10 is preferably mounted on a support 47 having suitable side flanges 48 constituting guides whereby the receptacle may be bodily moved forward or backward, and when properly adjusted the same is conveniently held in position as by a thumb bolt 49 passing through a threaded aperture in a suitable lug 50 intermediate the sides of the receptacle, which bolt 49 at its inner end is adapted to engage over an outwardly extending flange 51 at the lower end of said receptacle 10.

It is desirable to adapt the construction to various machines now in use and with this and other objects in view, it is proposed to permit of adjustment of the support 47 laterally relative to the machine whereby to align the paste carrying member with the label receptacle.

52 is a suitable bracket support adapted to be secured in any desired manner to the side of the framework of the machine and having at its upper end an elongated bar or bed plate 53. The plate 53 has in its upper surface a recessed portion 54 adapted for the support of a base 55 of the support 47, the side walls of the recess of the plate 53 constituting guides whereby to permit of adjustment of the support 47 longitudinally of said plate 53 or transversely of the machine. In order to maintain the support 47 in adjusted position on the plate 53 I preferably provide in the plate 53 an elongated recess 56 in the under surface of the plate, and a longitudinally extending slot 57 extending from the free end of the plate inwardly, and adapted to project through said slot and to be secured to the support 47 is a bolt 58 threaded to the support 47 and having a headed end 59 overlying the wall of the slot 57. Interposed between the wall of the recess 56 in the under surface of the plate 53 and the headed end of the bolt 58 is a suitable spring member 60, which latter is adapted to frictionally hold the support 47 in any of its adjusted positions.

The operation may be reviewed as fol-

70

75

80

85

90

95

100

105

110

115

120

125

130

lows: It being understood that the cans are led to the forward end of the runway in the usual manner, the foremost can being fed by the belt 5, will move over the pasting roller 3, thereby receiving an application of paste, which in the continued movement of the can will engage the forward end of the label to pick up the same and in its further movement will wind the label thereabout, it being understood that the lap end of the label is receiving an application of paste by the endless paste carrier and that said lap end will be secured to the can by the continued movement of the can, which latter is pressed by the belt 5 against the usual ironing or pressing pad not shown, at the rear end of the machine. As a can moves into contact with the plates 30, the latter are lowered into contact with the runway, constituting in the lowered position practically a continuation of the runway, and since the connected parts of the plates 30 are positioned to the side of the runway and therebelow, they will not interfere with the movement of the can. As the plates 30 are lowered the spring arms carried thereby lower the operative end of the endless paste carrying member into engagement with the lap end of the label, when the plates 30 will be elevated by the springs 29 and the forward end of the paste carrying member with the uppermost label will be likewise elevated by its spring 25. When the endless paste carrying member is in contact with the label, it is stationary, but the same is given an intermittent movement lengthwise while out of contact with the labels, the same being accomplished by the continued movement of the can which moves into contact with the plate 42, thereby rocking the arm 40 and through the dog 46 moving the segment wheel 38 and therewith the gear wheel 12, which in turn imparts rotary movement to the pinion 13, thereby rotating the roll 16 and the toothed wheels at the ends thereof. The said toothed wheels being in engagement with the chains at the sides of the endless paste carrying belt imparts rotary movement to the latter. As soon as the plate 42 has been disengaged by the can in its continued movement, the arm 40 carrying said plate is elevated by the spring 43 to the position illustrated in Figs. 1 and 5.

By the peculiar construction of endless paste carrier it will be observed that the same while flexible from side to side and end to end, whereby it will readily engage the label, at the same time the paste carrying member is reinforced at its sides through the medium of the chain borders, thereby overcoming the usual twisting of the belt in movement and preventing stretching of the same.

In practice the labels are usually inserted

from the rear end of the label receptacle 6, and by reason of the longitudinal adjustment of the lap end pasting mechanism it will be appreciated that the same may be moved rearwardly so as to offer no hindrance to the ready positioning of the labels in the receptacle. Also as desired, the said lap end pasting mechanism may be bodily removed sidewise from the machine by simply drawing the same out, the guide slot in the plate 53 extending to the edge of said plate for this purpose. It will also be seen that the gear connection between the paste roll and supporting roll for the endless paste carrying member of the lap end pasting mechanism is positioned to one side of the receptacle 10, and by removing the members 11^b and 46^a on the shafts at one side of the receptacle 10, the said shafts may be bodily removed from the opposite side of the receptacle. This will free the paste roll 11 and the carrying frame for the endless paste belt. The trip arm 42 may also be removed sidewise of the machine upon removal of the shaft 11^a, the support 45 for the spring arm 43 connected to the arm 40 having a terminal slot for this purpose.

Referring now more particularly to Figs. 7, 8 and 9, which disclose the preferred form of trip actuated means for moving the belt lengthwise, it will be observed that the gear wheel 12, together with the intermeshing pinion 13 is employed as previously described for operating the paste belt 24. Also connected for movement with the gear wheel 12 is the ratchet wheel 38. The means for causing the ratchet wheel to rotate to thereby impart rotary movement to the paste belt in the present embodiment of the invention is somewhat differently constructed as follows: An upright bracket support 61 is provided, the same being preferably interposed between the ratchet wheel 38 and the adjacent side of the paste receptacle, being removably secured to the latter as by screws 62. One member 63, of what may be termed a toggle link, preferably has a bifurcated terminal 63^a fitted over the upper end of the support 61 and is pivotally connected thereto, as by a pintle 64. The other member 65 of the toggle link has connected thereto a pawl 66, the latter being conveniently an integral extension of the member 65. The members 63 and 65 are pivotally connected, as by a pivot bar or rod 67 passing through registered apertures in the terminals of said members which lie side by side. Projecting inwardly from the member 63 of the toggle link is a plate 67^a which said plate is of a length to overlie the adjacent runway and is adapted in the movement of the can to be engaged by the latter and depressed thereby, imparting a substantially direct downward movement to the pawl 66, which being in engagement with the ratchet

70

120

125

130

wheel 38 will rotate the latter and in turn the gear wheel 12, pinion 13 and the drive sprocket for the paste belt. In order to hold the pawl member of the toggle link in operative position relative to its ratchet wheel and in order also to maintain the trip plate 67^a in an elevated position to be engaged by the can, I preferably provide a coil spring 68, the latter being sleeved upon the pivot bar 67 and connected at one end to a collar 69 adapted to be secured to the rod 67 as by a screw 70. The opposite end of said coiled spring is connected to the pawl member at 71. The action of said spring is to draw 15 the pawl member inwardly and buckle the members of the toggle link whereby the pawl will be maintained in operative engagement with the ratchet wheel and whereby the member 63 of the toggle link positions 20 the pressure plate 67^a above the runway and in position to be engaged by the can. A stop is provided for limiting the upward movement of the toggle link due to the action of said spring, the said stop preferably taking 25 the form of a bracket member 72 secured to the support 61 which said bracket member preferably has an adjustable screw 73 adapted to engage the upper surface of the member 63. By adjusting the screw 73 the upward limit of the movement of the toggle 30 link may be accurately adjusted and positioned. Also to regulate the tension of the spring 68 it is simply necessary to loosen the screw 70 when the collar 69 may be rotated upon the rod 67 and afterward held 35 in adjusted position by the screw 70. In this embodiment of the invention it is preferable to arrange the means for limiting the upward movement of the carrier frame 40 for the paste belt at the opposite end or side of the paste receptacle as illustrated in Fig. 9. This bracket is given the numeral 74 and is adjustably connected at 75 to the side of the paste receptacle having an overhanging arm at its upper end to engage over the 45 swining frame 17'.

The toggle link form of trip member has certain material advantages, notably the fact that the same is more easily operated by the 50 passing can due to the substantially direct downward pressure on the member 63 caused by the pressure on the can by the feed belts.

It will be noted that in both embodiments of the invention illustrated, the trip plates 55 42 and 67 respectively are of a length to overlie the runway bar at that side of the machine and projecting rearwardly from one side of the trip plate is an inclined offset part 42^a for the plate 42 and 67^b for the 60 plate 67. This is of especial advantage since it oftentimes happens that a reverse movement is given to the cans on the runway, and should said cans in the reverse movement meet with an abrupt edge, the parts are 65 likely to become broken, whereas in the pres-

ent case the downwardly inclined portions 42^a and 67^b of the respective presser plates will be engaged by a can in a reverse movement thereof along the runway and the trip plates will be thereby lowered, preventing 70 injury to the parts.

I claim:—

1. In a can labeling machine, a can runway, a label support intermediate the ends of the runway and over which the article to 75 be labeled passes, and lap end pasting means comprising a lengthwise movable paste applying member, and means for moving the said member up and down or into and out of contact with the supply of labels on the 80 support.

2. In a can labeling machine, a can runway, a label support intermediate the ends of the runway and over which the article to be labeled passes, lap end pasting means 85 comprising a lengthwise movable paste applying member, and means controlled by the movement of a can along the runway for moving the said member up and down or into and out of contact with the supply of 90 labels on the support.

3. In a can labeling machine, a can runway, a label support, label pick up pasting means, lap end pasting means comprising an endless belt, means for positively moving the 95 belt up and down into and out of contact with the lap end of stack of labels on the support, and means for imparting rotary movement to the belt when in raised position.

4. In a can labeling machine, a can runway, a label support intermediate the ends of the runway and over which the article to be labeled passes, label pick up pasting means, lap end pasting means comprising an 105 endless belt, means for positively moving the belt up and down into and out of contact with the stack of labels on the support, and means controlled by the movement of a can along the runway for imparting rotary 110 movement to the belt when in raised position.

5. In a can labeling machine, a can runway, a label support, label pick up pasting means, lap end pasting means comprising a 115 movable belt normally raised above the label support, and means for bodily moving the belt up and down, into contact with the lap end of the label positioned on said support.

6. In a can labeling machine, a can runway, label pick up pasting means, a label support over which the can is adapted to roll and pick up the label, lap end pasting means comprising a movable belt normally raised above the label support, and means 125 for moving one end of the belt up and down, into contact with the lap end of the label positioned on said support.

7. In a can labeling machine, a can runway, label pick up pasting means, a label 130

- support over which the can is adapted to roll and pick up the label, lap end pasting means comprising means engaging the belt for normally elevating the belt above the labels on the support, and independent means for moving the belt down into contact with the lap end of uppermost label.
8. In a can labeling machine, a can runway, label pick up pasting means, a label support intermediate the ends of the runway over which the can passes to pick up the labels, lap end pasting means comprising means controlled by the movement of the can for normally elevating the belt above the labels on the support, and means controlled by the movement of the can for moving the belt down into contact with the uppermost label.
9. In a can labeling machine, a can runway, label pickup pasting means, a label support, lap end pasting means comprising means movable toward and from the labels for supplying paste to the lap end of the uppermost label and lifting the same from the stack of labels, as the same is wound about the can.
10. In a can labeling machine, a can runway, a label support, pasting means for one end of the label and independent means for supplying paste to the lap end of the label comprising a belt, a movable carrying frame for the belt, means for moving the belt on the frame, means for moving the frame to contact the belt with the lap end of the label, and means for normally holding the belt out of contact with the label stack.
11. In a can labeling machine, a can runway, label pick up pasting means, a label support intermediate the end of the runway over which the can passes to pick up the labels, and means for supplying paste to the lap end of the label comprising a belt, a swinging carrying frame for the belt, means for moving the belt on the frame, means for moving the frame to contact the belt with the lap end of the label, and means for normally holding the belt out of contact with the label stack.
12. In a can labeling machine, a can runway, label pick up pasting means, a label support intermediate the ends of the runway over which the can passes to pick up the labels, and means controlled by the movement of a can along the runway for supplying paste to the lap end of the label comprising a belt, a movable carrying frame for the belt, means for moving the belt on the frame, means for moving the frame to contact the belt with the lap end of the label, and means for normally holding the belt out of contact with the label stack.
13. In a can labeling machine, a can runway, label pick up pasting means, a label support intermediate the ends of the runway over which the can passes to pick up
- the labels, and means controlled by the movement of a can along the runway for supplying paste to the lap end of the label comprising a belt, a swinging carrying frame for the belt, means for moving the belt on the frame, means for moving the frame to contact the belt with the lap end of the label, and means for normally holding the belt out of contact with the label stack.
14. In a can labeling machine, a can runway, a label support, and lap end pasting mechanism, the same including a swinging carrying frame, a paste belt carried by the frame, spring means for normally holding the frame to position the belt out of contact with the labels, and means controlled by a passing can and acting in opposition to the spring to move the frame and contact the belt with the topmost label.
15. In a can labeling machine, the combination of a can runway, label pick up pasting means, a label support intermediate the ends of the runway over which the can passes to pick up the labels, and lap end pasting mechanism, the same comprising a paste receptacle, a paste roll in the receptacle, an endless paste carrying belt movable in contact with the roll so as to receive paste therefrom, a movable carrying frame supported on the receptacle for said belt, and means for moving the frame to force the belt into and out of operative position relative to the supply of labels.
16. In a can labeling machine, the combination of a can runway, label pick up pasting means, a label support intermediate the ends of the runway over which the can passes to pick up the labels, and lap end pasting mechanism, the same comprising a paste receptacle, a paste roll, a shaft for the roll in the receptacle, an endless paste carrying belt movable in contact with the roll so as to receive paste therefrom, a roll support for said belt, a movable carrying frame supported on the shaft of the roll for said belt, and means for moving the frame to force the belt into and out of operative position relative to the supply of labels.
17. In a can labeling machine, the combination of a can runway, means for feeding a can along the runway, a label support intermediate the ends of the runway in the path of the rolling can, means for applying paste between one end of the label and can, and lap end pasting instrumentalities including a paste receptacle, an endless paste belt movable into contact with said roll so as to receive an application of paste therefrom, a pivoted carrying frame for the paste belt, and means for raising and lowering the same relative to the lap end of the supply of labels.
18. In a can labeling machine, the combination of a can runway, means for feeding

a can along the runway, a label support, and lap end pasting instrumentalities including a paste receptacle, a paste roll mounted on the receptacle, an endless paste belt movable 5 into contact with said roll so as to receive an application of paste therefrom, a pivoted carrying frame for the paste belt, and means for raising and lowering the same relative to the supply of labels, said means including 10 a trip arm adapted to be pressed downwardly by the moving can, said trip arm being operatively associated with the belt carrying frame.

19. In a can labeling machine, the combination of a can runway, a label support, 15 pasting means in advance of the label support to apply paste to the can whereby the latter will pick up a label on the support, lap end pasting instrumentalities arranged 20 at a point intermediate the ends of the runway including an endless paste belt lengthwise movable longitudinally of the machine and adapted to engage the lap end of a label, a movable carrier frame for the belt, and 25 means arranged in the path of the can adapted to be moved thereby into operative relation with the carrier frame to move the belt into and out of operative position relative to the labels.

30. 20. In a can labeling machine, the combination of a can runway, a label support, pasting means in advance of the label support to apply paste to the can whereby the latter will pick up a label on the support, 35 lap end pasting instrumentalities including an endless paste belt lengthwise movable longitudinally of the machine and adapted to engage the lap end of a label, a pivoted carrier frame for the belt, means normally 40 maintaining the carrier frame in one position with respect to the labels, and means for moving the carrier frame about its pivot in an opposite direction, said last mentioned means being governed by the movement of 45 the cans along the runway.

21. In a can labeling machine, the combination of a can runway, a label support, lap end pasting instrumentalities including an endless paste belt lengthwise movable longitudinally of the machine and adapted to engage the lap end of a label, a pivoted carrier frame for the belt, and means adapted to be traveled over by a passing can and to contact with said pivoted carrying frame to 55 lower the same and with it the belt into contact with the labels.

22. In a can labeling machine, the combination of a can runway, a label support, lap end pasting instrumentalities including an 60 endless paste belt lengthwise movable longitudinally of the machine and adapted to engage the lap end of a label, means for moving the belt into contact with the label including an actuating device supported from

the label receptacle and adapted to be actuated by means controlled by a passing can. 65

23. In a can labeling machine, the combination of a can runway, can feeding means, can pick-up pasting means, a label support, and lap end pasting mechanism comprising 70 a paste receptacle arranged below the runway and rearwardly of the label receptacle, a paste belt adapted to receive an application of paste from the receptacle and movable longitudinally of the machine, and 75 means for moving the belt vertically into and out of contact with the label.

24. In a can labeling machine, the combination of a can runway, can feeding means, 80 can pick up pasting means, a label support, and lap end pasting mechanism comprising a paste receptacle arranged below the runway and rearwardly of the label receptacle, a paste belt adapted to receive an application of paste from the receptacle and movable longitudinally of the machine, and 85 means for moving the forward end of the belt vertically into and out of contact with the label.

25. In a can labeling machine, pick-up 90 pasting appliances, a can runway, a label support, and lap end pasting mechanism for the label comprising an endless paste carrier belt movable longitudinally of the machine, 95 a carrier frame for said endless paste belt movable toward and from the labels, and a movable element arranged in the path of the cans which travel along the runway to be actuated thereby, said element being operatively associated with the carrier frame 100 to position the belt alternately above, and in contact with the labels.

26. In a can labeling machine, pick up 105 pasting appliances, a can runway, a label support, and lap end pasting mechanism for the label comprising an endless paste carrier belt movable longitudinally of the machine, a carrier frame for said endless paste belt movable vertically toward and from the labels, means for normally holding the 110 carrier frame in position to place the belt above the labels, and means arranged in the path of, and adapted to be actuated by, a passing can to move the frame in an opposite direction to contact the belt with the 115 labels.

27. In a can labeling machine, the combination of a can runway, pick-up pasting appliances, a label support, and lap end pasting mechanism including an endless belt 120 movable toward and from the labels, means for holding the belt normally out of contact with the labels, and means for moving the belt into contact with the labels, including a trip arm adapted to be engaged by the can 125 in its movement along the runway, and means for forcing the can over the trip arm.

28. In a can labeling machine, the com-

5 combination of a can runway, pick-up pasting appliances, a label support, lap end pasting mechanism including an endless belt movable toward and from the labels, means for holding the belt normally out of contact with the labels, means for moving the belt into contact with the labels, including a trip arm adapted to be engaged by the can in its movement along the runway, and means for 10 forcing the can over the trip arm, said means also constituting the feed for the cans along the runway.

29. In a can labeling machine, the combination of a can runway, pick-up pasting mechanism, a label receptacle, a lap end pasting belt, and means for raising the lap end of the topmost label and belt from the stack of labels.

30. In a can labeling machine, the combination of a can runway, can pick-up pasting appliances, a label receptacle, and lap end pasting mechanism including a belt lengthwise movable longitudinally of the machine, a paste receptacle for supplying paste to the belt, means actuated by the movement of the cans along the runway to move the belt into and out of contact with the labels in the receptacles and means whereby the receptacle with the belt may be 35 bodily moved from the side of the machine.

31. In a can labeling machine, the combination of a can runway, can pick-up pasting mechanism, a label support open at its rear end, lap end pasting mechanism, the same including a paste receptacle positioned below the runway to the rear of the label receptacle, a paste belt adapted to receive a supply of paste from the receptacle and transmit the same to the uppermost label, 40 means for imparting vertical movement to one end of the belt into and out of contact with the label, and means for adjusting the receptacle with the belt longitudinally of the machine.

45 32. In a can labeling machine, the combination of a can runway, can pick-up pasting mechanism, a label support open at its rear end, lap end pasting mechanism, the same including a paste receptacle positioned below the runway to the rear of the label receptacle, a paste belt adapted to receive a supply of paste from the receptacle and transmit the same to the uppermost label, 50 means for imparting vertical movement to one end of the belt into and out of contact with the label and means for adjusting the receptacle with the belt longitudinally of the machine whereby to position the lap end pasting mechanism to a point rearwardly of the label receptacle where it offers no obstruction to the introduction of the labels to said receptacle.

55 33. In a can labeling machine, the combination of a can runway, can pick-up pasting mechanism, a label support open at its

rear end, lap end pasting mechanism, the same including a paste receptacle positioned below the runway to the rear of the label receptacle, a paste belt adapted to receive a supply of paste from the receptacle and transmit the same to the uppermost label, 70 a trip arm operatively associated with the belt and adapted to be actuated by the movement of a can along the runway to automatically position the belt with respect to the labels, means for adjusting the receptacle with the belt longitudinally of the machine, and means for bodily removing the paste receptacle with the parts associated therewith sidewise of the machine.

75 34. In a can labeling machine, the combination of a can runway, a label support intermediate the ends of the runway and below the path of the can, pasting instrumentalities including a pasting member of a 80 length to engage from side to side of the label, and means for supporting the pasting member whereby the latter conforms to the usual curve or sag of the supply of labels.

85 35. In a can labeling machine, the combination of a can runway, a label receptacle intermediate the ends of the runway and below the path of the can, lap end pasting means including a belt adapted to be positioned over the labels, and a curved supporting member for the operative surface of said belt.

90 36. In a can labeling machine, the combination with a can runway, a label support intermediate the ends of the runway and below the path of the can, and lap end pasting mechanism for the labels including an endless belt, a supporting bar intermediate the folds of the belt, said bar having associated means for carrying one portion of the operative surface of the belt lower than the other portion thereof.

95 37. In a can labeling machine, the combination of a can runway, a label support intermediate the ends of the runway, and lap end pasting mechanism for the labels including an endless belt, a supporting bar intermediate the folds of the belt, said bar being curved.

100 38. In a can labeling machine, a can runway, a label support positioned below the runway, and lap end pasting instrumentalities for the labels comprising a belt, a roller support for one end of the belt, a bar for supporting the opposite end of the belt, said 105 bar being curved longitudinally.

110 39. In a can labeling machine, a runway, a label support positioned below the runway, and lap end pasting instrumentalities for the labels comprising a belt, a roller support for one end of the belt, a substantially U-shaped pivot bar with the connecting arm thereof constituting a support for the opposite end of the belt.

115 40. In a can labeling machine, a label sup-

- port positioned below the runway, lap end pasting instrumentalities for the labels comprising a belt, a roller support for one end of the belt, and a substantially U-shaped pivot bar with the connecting arm thereof constituting a support for the opposite end of the belt, said bar being lengthwise adjustable relative to the belt.
41. In a can labeling machine, a label support positioned below the runway, lap end pasting instrumentalities for the labels comprising a belt, a roller support for one end of the belt, a substantially U-shaped pivot bar with the connecting arm thereof constituting a support for the opposite end of the belt, the connecting arm of said bar being curved longitudinally.
42. In a can labeling machine, the combination of a runway, a label support, lap end pasting appliances comprising a paste receptacle, a paste roll mounted on the receptacle, a rotatable roll also mounted on the receptacle and constituting a support for one end of an endless paste carrying belt adapted to receive paste from said paste roll, said endless belt, and a lengthwise adjustable pivoted support carried by the shaft of the roll support for the endless carrier, said pivoted support engaging at its end one end of the endless paste carrier.
43. In a can labeling machine, the combination of a runway, a label support, lap end pasting appliances comprising a paste receptacle, a paste roll mounted on the receptacle, a rotatable roll also mounted on the receptacle and constituting a support for one end of an endless paste carrying belt adapted to receive paste from said paste roll, said endless belt, and a lengthwise adjustable pivoted support carried by the shaft of the roll support for the endless carrier, said pivoted support engaging at its end one end of the endless paste carrier, and means governed by the movement of a can along the runway for engaging said pivoted support to move the endless paste carrier into contact with the labels.
44. In a can labeling machine, a can runway, a label support intermediate the ends of the runway in the path of the can, a paste applying belt to engage the topmost label on the support, said belt comprising a body of yieldable material and a border of substantially non-yieldable material.
45. In a can labeling machine, a can runway, a label support intermediate the ends of the runway in the path of the can, a paste applying belt to engage the topmost label on the support, said belt comprising a body of yieldable material and a metallic border.
46. In a can labeling machine, a can runway, a label support intermediate the ends of the runway, in the path of the can, a paste applying belt to engage the topmost
- label on the support, said belt comprising a body of yieldable material, a metallic border, and means engaging the border to rotate the belt.
47. In a can labeling machine, a can runway, a label support intermediate the ends of the runway in the path of the can, a paste applying belt to engage the topmost label on the support, said belt comprising a body of yieldable material, a metallic border, and means engaging the border to rotate the belt, said border having a series of openings, and a rotatable toothed wheel to engage the openings of said border to impart rotary movement thereto.
48. In a can labeling machine, a can runway, a label support intermediate the ends of the runway in the path of the can, a paste applying belt to engage the topmost label on the support, said belt comprising a body of yieldable material, and side borders for said body portion taking the form of chains, and gear wheels to engage said chains and thereby impart rotary movement to the belt.
49. In a can labeling machine, a can runway, a label support intermediate the ends of the runway in the path of the can, a paste applying belt to engage the topmost label of the support, said belt comprising a body of yieldable material, and side borders for said body portion taking the form of chains, and gear wheels to engage said chains and thereby impart rotary movement to the belt, said gear wheels being rotatable intermittently.
50. In a can labeling machine, a can runway, a label support, a paste applying belt to engage the topmost label of the support, said belt comprising a body of yieldable material, side borders for said body portion taking the form of chains, gear wheels to engage said chains and thereby impart rotary movement to the belt, said gear wheels being rotatable intermittently, and means governed by the movement of a can along the runway for operating said gear wheels intermittently.
51. In a can labeling machine, a can runway, a label support, a paste applying belt to engage the topmost label of the support, said belt comprising a body of yieldable material, side borders for said body portion taking the form of chains, gear wheels to engage said chains and thereby impart rotary movement to the belt, said gear wheels being rotatable intermittently, and means governed by the movement of a can along the runway for operating said gear wheels intermittently including a rotatable wheel adapted to rotate the gear wheels, and a trip arm having connection with said wheel extending across the runway to be traversed by a fed can.
52. In a can labeling machine, a can run-

way, a label support, a paste applying belt to engage the topmost label of the support, said belt comprising a body of yieldable material, side borders for said body portion 5 taking the form of chains, gear wheels to engage said chains and thereby impart rotary movement to the belt, said gear wheels being rotatable intermittently, and means governed by the movement of a can along 10 the runway for operating said gear wheels intermittently including a pinion operatively connected with one of said gear wheels, an enlarged rotatable gear wheel in engagement with said pinion, a ratchet 15 wheel carried by the enlarged gear wheel, and a pivoted dog having a connected part to be engaged by a passing can.

53. In a can labeling machine, a can runway, a label support, a paste applying belt 20 to engage the topmost label of the support, said belt comprising a body of yieldable material, side borders for said body portion taking the form of chains, gear wheels to engage said chains and thereby impart 25 rotation to the runway for operating said gear wheels being rotatable intermittently, and means governed by the movement of a can along the runway for operating said gear wheels intermittently including a pinion operatively 30 connected with one of said gear wheels, an enlarged rotatable gear wheel in engagement with said pinion, a ratchet wheel carried by the enlarged gear wheel, a pivoted arm having a trip plate to be engaged by a passing can, and a dog at one 35 end of the rock arm to engage said ratchet wheel.

54. In a can labeling machine, a can runway, a label support, a paste applying belt 40 to engage the topmost label of the support, said belt comprising a body of yieldable material, side borders for said body portion taking the form of chains, gear wheels to engage said chains and thereby impart 45 rotary movement to the belt, said gear wheels being rotatable intermittently, means governed by the movement of a can along the runway for operating said gear wheels intermittently including a pinion operatively 50 connected with one of said gear wheels, an enlarged rotatable gear wheel in engagement with said pinion, a ratchet wheel carried by the enlarged gear wheel, a pivoted arm having a trip plate overlying the runway to be engaged by a passing can, a dog pivoted to the 55 rock arm to engage said ratchet wheel, and spring means for holding the arm with the trip plate in operative position to be engaged by the can.

55. In a can labeling machine, the combination of a can runway, a label receptacle, a paste receptacle at the rear end of the label receptacle, a lengthwise movable belt extending longitudinally of the machine and 60 adapted to receive paste from the receptacle,

and means for supporting the receptacle whereby the same may be adjusted longitudinally relative to the machine to space the same from the label receptacle and to govern the extent of overlap of the belt on the labels, and means for moving the belt vertically in the movement of the cans along the runway. 70

56. In a labeling machine, the combination of a runway, pasting devices to apply a daub of paste to the can, a label receptacle arranged below the runway having an open rear end, a paste receptacle arranged below the runway to the rear of the label receptacle, a lengthwise movable belt positioned in the paste receptacle and normally overlying a supply of labels in the label receptacle, means for adjusting the paste receptacle longitudinally of the machine, and a support for the paste receptacle removable sidewise 75 of the machine. 80

57. In a can labeling machine, label pick-up pasting appliances, a runway, a label support, a lap end pasting mechanism including a paste pot, a paste roll, a shaft for the roll keyed thereto, an endless paste belt, a roll for one end of the belt, a shaft for the belt roll, and means whereby both shafts may be removed by a sliding movement so as to release the rolls and belt for removal 90 from the receptacle. 95

58. In a can labeling machine, label pick-up pasting appliances, a runway, a label support, a lap end pasting mechanism including a paste pot, a paste roll, a shaft for the roll keyed thereto, an endless paste belt, a roll for one end of the belt, a shaft for the belt roll, a driving connection between the shafts to the outside of the receptacle, and means whereby the shafts with the driving connection may be removed from one side of the receptacle so as to release the rolls and belt. 100 105

59. In a labeling machine having a runway, a label support and pick-up paste appliances, the combination of a lap end pasting mechanism including an endless paste applying belt positioned over a supply of labels, means for holding the belt in a normally stretched condition and above the labels, and means for moving the belt while maintaining its normally stretched condition into and out of contact with the lap end labels. 110 115

60. In a labeling machine, the combination of a runway, a label support, label pick-up pasting means, and means for applying paste to the lap end of the label including a paste applying member projecting across the labels and normally spaced therefrom, a vertically movable carrying frame for the pasting member, and means movable into contact with the frame to lower the paste member into contact with the label positioned on said support. 120 125 130

61. In a labeling machine, the combination of a runway, a label support, label pick-up pasting means, means for applying paste to the lap end of the label including 5 a paste applying member projecting across the labels and normally spaced therefrom, a vertically movable carrying frame for the pasting member, means movable into contact with the frame to lower the paste member into contact with the label positioned on said support, and spring means for normally holding said carrying frame with the paste member out of contact with the labels.

62. In a labeling machine, the combination of a runway, a label support, label pick-up pasting means, means for applying paste to the lap end of the label including a paste applying member projecting across the labels and normally spaced therefrom, 20 a vertically movable carrying frame for the pasting member, means movable into contact with the frame to lower the paste member into contact with the label positioned on said support, and can actuating means for 25 intermittently moving the paste member lengthwise.

63. In a can labeling machine, the combination of a runway, a label support, lap end pasting appliances including a paste carrying member normally arranged above the labels on the support, and means for bodily moving the paste carrying member into contact with the labels including a spring arm actuated by a passing can.

64. In a can labeling machine, the combination of a runway, a label support, lap end pasting appliances including a paste carrying member normally arranged above the labels on the support, and means for forcing 40 the paste carrying member into contact with the labels including a pivoted arm arranged in the path of the can and adapted to be actuated by the latter to depress the paste carrying member.

65. In a can labeling machine, the combination of a runway, a label support, lap end pasting appliances including a paste carrying member normally arranged above the labels on the support, means for forcing the 50 paste carrying member into contact with the labels including a pivoted arm arranged in the path of the can and adapted to be actuated by the latter, and a spring arm carried by the pivoted arm to move the carrier so as to operatively position the paste carrying member.

66. In a can labeling machine, the combination of a runway, a label support, lap end pasting appliances including a paste carrying member normally arranged above the labels on the support, and means for forcing the paste carrying member into contact with the labels including a pivoted arm yieldably held in position to be depressed by a

can, said arm being operatively associated 65 with the paste carrying member.

67. In a labeling machine, the combination of a runway, means for applying one end of a label to the can, a label support, a paste carrier, and means for moving the carrier into contact with the lap end of the label including a pivoted arm having an angle extension at one end overlying the runway, means for normally holding the arm elevated, and said arm being adapted 75 to be depressed into operative position to depress the paste carrier into contact with the label.

68. In a labeling machine, the combination of a runway, means for applying one 80 end of a label to the can, a label support, a paste carrier, means for moving the carrier into contact with the lap end of the label including a pivoted arm having an angle extension at one end overlying the runway, 85 means for normally holding the arm elevated, said arm being adapted to be depressed into operative position to depress the paste carrier into contact with the label, and means for automatically moving said 90 carrier out of contact with the label.

69. In a labeling machine, the combination of a runway, means for applying one end of a label to a can, a label support, a paste carrier, means for moving the carrier 95 into contact with the lap end of the label including a pivoted arm having an angle extension at one end overlying the runway, means for normally holding the arm elevated, said arm being adapted to be depressed into operative position to depress the paste carrier into contact with the label, means for automatically moving said carrier out of contact with the label, and means for moving the carrier lengthwise when it 100 is in the last mentioned position.

70. In a labeling machine, the combination of a runway, means for applying one end of a label to the can, a label support, a paste carrier, means for moving the carrier 110 into contact with the lap end of the label including a pivoted arm having an angle extension at one end overlying the runway, means for normally holding the arm elevated, said arm being adapted to be depressed into operative position to depress the paste carrier into contact with the label, and spring controlled means for automatically moving said carrier with the belt out 115 of contact with the labels, and means controlled by the movement of the can to intermittently move the paste carrier lengthwise.

71. In a labeling machine, the combination of a runway, means for applying one end of a label to the can, a label support, an endless paste carrier, means for moving the carrier into contact with the lap end of the label including a spring held pivoted arm on the 125

label support having a lateral projection extending across the path of the can and adapted to be moved by the latter against the action of its spring to force the carrier into contact with the top-most label on the support.

72. In a labeling machine, the combination of a runway, means for applying one end of a label to the can, a label support, a paste carrier, means for moving the carrier into contact with the lap end of the label including a spring held pivoted arm on the label support having a lateral projection extending across the path of the can and adapted to be moved by the latter against the action of its spring to force the carrier into contact with the top-most label on the support, and means for automatically returning the carrier to a position away from the labels.

73. In a labeling machine, the combination of a runway, means for applying one end of a label to a can, a label support, a paste carrier, means for moving the carrier into contact with the lap end of the label including a spring held pivoted arm on the label support having a lateral projection extending across the path of the can and adapted to be moved by the latter against the action of its spring to force the carrier into contact with the top-most label on the support, said carrier being lengthwise movable to present a new surface to successive labels.

74. In a labeling machine, the combination of a runway, means for applying one end of a label to a can, a label support, a paste carrier, means for moving the carrier into contact with the lap end of the label including a spring held pivoted arm on the label support having a lateral projection extending across the path of the can and adapted to be moved by the latter against the action of its spring to force the carrier into contact with the top-most label on the support, said carrier being lengthwise movable by the movement of a can along the runway to present a new surface to successive labels.

75. In a labeling machine, the combination of a runway, means for applying one end of a label to the can, a label support, a paste carrier, means for moving the carrier into contact with the lap end of the label including a spring held pivoted arm on the label support having a lateral projection extending across the path of the can and adapted to be moved by the latter against the action of its spring to force the carrier into contact with the top-most label on the support, and a spring interposed between the carrier and said lateral projection.

76. In a labeling machine, the combination of a runway, means for feeding the can along the runway, a label support, means for applying paste to the lap end of the label including an endless belt, means for mov-

ing the belt vertically and an intermittent feed for moving the belt lengthwise, said feed being actuated by a trip arranged adjacent the runway and adapted to be forced down by the can.

77. In a can labeling machine, a runway, a label support, lap end pasting means including a lengthwise movable belt extending longitudinally of the machine, means for moving the belt vertically and means for intermittently moving said belt lengthwise including a trip adapted to be traversed and operated by a passing can.

78. In a machine of the character described, the combination of a runway, label pick-up pasting appliances, a label support, and lap end pasting mechanism including an endless paste carrying belt, means for moving the belt vertically and means for moving the same lengthwise intermittently including a pivoted arm operatively connected at one end to the belt and having a projection across the runway to be engaged by a can in its movement along the runway so as to move the belt.

79. In a machine of the character described, the combination of a runway, label pick-up pasting appliances, a label support, lap end pasting mechanism including an endless paste carrying belt, means for moving the belt vertically, means for moving the same lengthwise intermittently including a pivoted arm operatively connected at one end to the belt and having a projection across the runway to be engaged by a can in its movement along the runway so as to move the belt, and spring retaining means for said arm.

80. In a labeling machine, the combination of a runway, a label support, a paste receptacle, an endless paste carrying belt to apply paste to the lap end of the labels, and means for moving the belt vertically into contact with the labels including a member unconnected with the paste carrying member and adapted to be moved into operative position by a passing can.

81. In a labeling machine, the combination of a runway, a label support, a paste receptacle, an endless paste carrying belt to apply paste to the lap end of the labels, means for moving the belt vertically into contact with the labels including a member unconnected with the paste carrying member and adapted to be moved into operative position by a passing can, and driving mechanism for intermittently moving the belt lengthwise.

82. In a labeling machine, the combination of a runway, a label support, a paste receptacle, an endless paste carrying belt to apply paste to the lap end of the labels, means for moving the belt lengthwise including a trip member projecting across the runway and adapted to be traversed by a

passing can, said trip member normally having oppositely inclined ways whereby the can may travel over the same whether it be moved forward or backward, and means associated with the member to rotate the belt.

83. In a machine of the character described, the combination of a member to paste the lap end of the label, a can runway, means for intermittently actuating said pasting member including an operatively associated trip member arranged in the path of the can along the runway the can being adapted to move over said trip member and actuate the same, said member being also adapted to permit a reverse movement of the can thereover.

84. In a machine of the character described, the combination of a can runway, a label support, a member for pasting the lap end of the label, means for intermittently moving said member including an operatively associated trip member arranged in the path of a can to be actuated by the latter thereover whether the same is moved forwardly or backwardly along the runway.

85. In a machine of the character described, the combination of a can runway, a label support, a member for pasting the lap end of the label, means for intermittently moving said member including an operatively associated trip member arranged in the path of the can to be actuated by the latter, said trip member being in the form of a toggle link and carrying a projection extending across the runway over which the can passes.

86. In a machine of the character described, the combination of a can runway, a label support, a member for pasting the lap end of the label, means for intermittently moving said member including an operatively associated trip member arranged in the path of the can to be actuated by the latter, said trip member including two pivotally connected arms, one of which arms has a projection to be run over by a can, a pivotal connection for the free end of one arm, and means associated with the opposed arm to move the pasting member. 50

87. In a machine of the character described, the combination of a can runway, a label support, a member for pasting the lap end of the label, means for intermittently moving said member including an operatively associated trip member arranged in the path of the can to be actuated by the latter, said trip member including two pivotally connected arms, one of which arms has a projection to be run over by a can, a drive wheel for the pasting member, a ratchet operatively connected to the drive wheel and associated with the paste member to move the latter lengthwise, a pivotal connection for the free end of one arm, and a dog at the free end of the other arm to engage and actuate the ratchet wheel. 65

In testimony whereof I affix my signature in presence of two witnesses.

FREDERICK H. KNAPP.
